[57] CLAIM

The ornamental design for a wood burning heating stove, substantially as shown and described.

DESCRIPTION

FIG. 1 is a front elevational view of a wood burning heating stove, showing my new design;

FIG. 2 is a rear elevational view thereof;

FIG. 3 is a left side elevational view thereof;

FIG. 4 is a right side elevational view thereof; and

FIG. 5 is a top plan view thereof.

The bottom surface of the stove is substantially planar and unornamented.
